(57) **CLAIM**

We claim, the ornamental design for volatile substance evaporator, as shown and described.

DESCRIPTION

FIG. 1 is a front perspective view of a volatile substance evaporator, showing our new design;

FIG. 2 is front elevation view thereof;

FIG. 3 is a side elevation view taken from the right of FIG. 2;

FIG. 4 is a top plan view thereof;

FIG. 5 is a rear elevation view thereof;

FIG. 6 is a side elevation view taken from the left of FIG. 2; and,

FIG. 7 is a bottom plan view thereof.

The broken lines shown in the drawings are for illustrative purposes only and form no part of the claimed design.
